(57) **CLAIM**

The ornamental design for a post surgical mammary support bra, as shown and described.

DESCRIPTION

FIG. 1 is a front and right side perspective view of a post surgical mammary support bra showing my new design;

FIG. 2 is a front elevation view thereof;

FIG. 3 is a rear elevation view thereof;

FIG. 4 is a left side elevation view thereof;

FIG. 5 is a top plan view thereof; and,

FIG. 6 is a front and right side perspective view thereof showing the adjustment means at the sides, front, and the shoulder straps in an unhooked position.

The broken lines showing a female torso in FIGS. 1 to 4 are for illustrative purposes only and form no part of the claimed design.
